UNITED STATES PATENT OFFICE.

RUDOLPH B. HARTMAN, OF MILWAUKEE, WISCONSIN.

ADJUSTABLE PANEL-MOLD FOR CONCRETE FLOOR AND ROOF WORK.

1,209,151.

Specification of Letters Patent. Patented Dec. 19, 1916.

Application filed October 21, 1912. Serial No. 726,940.

To all whom it may concern:

Be it known that I, RUDOLPH B. HARTMAN, of Milwaukee, Wisconsin, have invented an Adjustable Panel-Mold for Concrete Floor and Roof Work, of which the following is a specification.

This invention relates to monolithic structural concrete, and has for its object, generally speaking, to facilitate, expedite, and generally improve the method and matter in which such work is erected, and my present invention is more particularly applicable to the construction of the floors and roofs of buildings, taken in connection with the columns and beams which support them.

More explicitly stated, my invention relates to certain novel construction of false-work used in setting up the floors, beams and columns, and to the method and manner of its erection and removal.

The construction of the falsework or wooden molds for the floors and roofs of concrete buildings, is, as well known to those skilled in the art, important and the most expensive part of concrete construction. At the present time it is customary to erect these in wood, the planks constituting the mold being cut to size and put in place piece by piece. This results in a great waste of material, demands the employment of skilled operators, and is more or less dangerous owing to the fact that in erecting the forms and until they are completed it is necessary for the operators to support themselves and walk around on ledges and in dangerous positions. Now according to my method these difficulties are largely or wholly dispensed with.

Briefly stated, the method consists in constructing panel-molds, each covering one panel of the floor, (that is so much of a floor as is included between three or more intersecting beams), including the sides of the beam, and subsequently hoisting them into place.

The invention further consists in a special construction for such panel molds, whereby I am enabled to use the least material to the greatest effect, and moreover to use said material over and over again with little or no waste; and further, in a construction whereby a panel mold of any desired size may be assembled in a minimum time, and after the concrete is set may be removed in

a minimum time and with a minimum of 55 labor.

This invention further consists in an improved system of supports for the beam-bottoms and panel-molds, enabling the panel-molds, including the side-facing 60 boards of the beams, to be removed quickly from the work after the concrete has been poured and has sufficiently set, without disturbing the supports for the beam bottoms, which require to be left to set a longer time 65 before they are removed.

The invention further consists in a section: 1 adjustable mold constructed jointly of wood and sheet-metal, which can be adjusted to fit any floor-panel, can be used an 70 indefinite number of times, can be set up very rapidly with little or no cutting or fitting, and makes possible a far greater variety of forms for the panels and beams than has heretofore been practicable. In 75 fact my construction enables me, without any additional expense in the construction, to decorate the surfaces of columns, beams and ceilings with ornamental capitals, moldings, and rosettes and the like, and to vary 80 these to an infinite number of patterns.

My invention further consists in the constructions, combinations and other features which are hereinafter described and more particularly set forth in my claims. 85

In the accompanying drawings I have shown several forms of my invention to enable the principle thereof to be readily apprehended, and herein—

Figure 1 is a plan of a sectional panel-form or mold constructed according to my invention; Fig. 2 is a bottom plan of a similar mold; Fig. 3 shows in transverse section two panels of the same construction, the section plane being indicated by the line 3 in 95 Figs. 1 and 2; Fig. 4 is a perspective view from the under side of one of the sections of the side-pieces of the same panel-mold; Fig. 5 is a perspective view from the under-side of one of the corner-pieces of the same with 100 an inset; Fig. 6 is a perspective view of an ornamental inset-piece for the column-corner of the panel; Fig. 7 is a fragmentary transverse section through portions of two panels showing an intermediate beam-form and support; Fig. 8 is a plan of another form of adjustable panel-mold; Fig. 9 is a transverse section through two panels 105

of the same construction on the planes indicated by the lines 9^a and 9^b in Fig. 8; Figs. 10, 11 and 12 are end-views of differently formed side-sections for similarly constructed molds; Figs. 13 and 14 are respectively a front view of a transverse section of an ornamental molded section for such a mold; Figs. 15 and 16 are transverse-sections showing two forms of my adjustable 10 plank for center filling; Figs. 17 and 18 are respectively a plan and transverse section on the plane 18 through a simplified construction of a corner of a panel-mold, in which the special corner-piece is dispensed 15 with; Fig. 19 is a plan-view of a panel-mold showing a somewhat different arrangement of the center-planks and adapted for an ornamental ceiling rosette and adapted also for a center column instead of an intermediate 20 column; Fig. 20 is an ornamental ceiling rosette or center-piece which may be used with the form of mold shown in Fig. 19; Fig. 21 is a plan-view of a panel-mold adapted to produce a paneled or tessellated ceiling; Fig. 22 is a plan of the frame of a continuous mold for paneled ceilings, or those in which the beam runs in one direction only; Figs. 23 and 24 are respectively an elevation 25 and a transverse section of a side-section 30 with strengthening means for the flat surface; and Figs. 25 and 26 are similar views of another form of the same.

My sectional mold in its most approved form may be used for any dimension of 35 floor-panel, and may be used over and over again without injury. As illustrated in Figs. 1, 2 and 3, it comprises four side-members and four corner-members; each side-member being made up in sections 40 35 (which may or may not be all the same size) joined end to end in a manner herein-after described, and the corner-members designated 32 being placed so as to overlap the side-members a variable distance. Further, 45 where (as is usually the case) there is a column in one corner of the panel, a special corner-member 33 is provided, having the corner thereof cut out and adapted for laying in its place a special corner-inset 34.

One of the side-member sections 35 is shown in perspective in Fig. 4, while it may be made in a number of different ways, that shown is deemed preferable. A single sheet 50 of metal is folded lengthwise to form a side-surface 36 and a top-surface 37, on the ends of which are preferably turned stiffening-flanges 38 and 39; the whole being supported and stiffened by transverse-brackets or gussets 40. These latter may be made 55 either of sheet-metal or wood, but experience has shown that they are both cheaper and more effective if made of wood as shown in the illustration, offering greater stiffness, and moreover greater ease of construction 60 since the sheet-metal can be simply nailed

onto the wooden gussets, and the latter can be used to give the metal its shape. The flange 39 should have a depth equal to one of the planks 30 or 31, which are used for the center filling, so as to bring the face 37 70 substantially flush therewith. The gussets 40 may be set to half the thickness of a plank inside the end of the section, so that when two sections are placed end to end there will be a space equal to the thickness 75 of a plank between the gussets, this space forming a seat for the end of an edgewise set plank 41, which forms a frame-beam. The two adjacent sections and the plank 41 are secured together by bolts 42 passing 80 through holes 43 in the gussets, and nails or other fastenings may also be used to secure them together. Where, as shown, the side-face 36 of the panel-mold is oblique, the ends of the planks 41 are preferably cut to a like 85 obliquity, so that their lower edges bear on the flanges 38.

As shown in the drawing, a cross-beam 41 extends from side to side at the ends of each section 35 on the longest side, and these beams may consist, if desired, of a single piece, but where the dimensions of the panels from one floor to the next vary, it will be desirable to form them of two planks 41 spliced together as shown, whereby only 90 one end of each plank is cut on the bevel, and the two planks are nailed together to the proper length in setting up the panel. However, it is not essential that this special construction be adopted, nor is it essential 95 to my invention that the gussets should be set as shown, nor that the cross-beams should come at the ends of the panels. It should be understood that the sheet-metal used in the construction of the panels is 100 ordinarily so thin that one section of the side may overlap the adjacent one, and additional gussets may be nailed on to the sections from time to time in any position 105 where it may be found desirable to use them 110 for the support of the cross-beams.

The shorter sides are supported in turn from the planks 41 by means of a set of short planks 45, each having also one end 115 cut on the bevel, and secured to the ends of a section in the same manner as the planks 41, and having their other end abutting against the adjacent plank 41 and nailed or otherwise secured thereto. To stiffen the frame thus formed in raising it into place 120 a longitudinal plank 46 may be nailed along the under-side to each of the planks 41 and opposite planks 45, and one or more of the filling-planks may also be nailed to the planks 41. These filling-planks 30 and 31 125 are laid upon the cross-beams 41 to fill the open central space, and, as disclosed in my prior application, Serial No. 422,537, filed March 21, 1909, they are not intended to 130 close the space entirely, but to support the

sheet-metal which is laid upon them, and directly support the concrete. According to my improved construction herein described, however, I have provided the adjustable planks 30 and 31, which are illustrated separately in Figs. 15 and 16. According to this construction, the edges of the planks are beveled on both edges (Fig. 15) or only on one edge (Fig. 16), which makes a number 5 of said planks laid in series adjustable to any desirable width. To obtain the desired width, it is merely necessary to take one more plank than the total number which will when set with the wide side up completely fill the space, and then reverse one or more of the planks, until the total width of the series is brought down to the required width. Where one edge only is beveled, the adjustment for a given angle of bevel can 10 be carried out more accurately than where both edges are beveled; and if desired, both kinds of plank may be used in combination. The use of this improved adjustable plank 15 renders a sheet-metal covering unnecessary provided the plank be cut to the proper length; and even this is not necessary where the construction of Fig. 19 hereinafter described is employed.

The side-pieces and end-pieces of the mold 20 having been united together in proper relation with the cross-beams 41 and planks 45, and the whole stiffened by the plank 46 in the manner described, is hoisted into place as a unit upon the beam-forms or beam-25 bottoms, which are supported in the usual manner upon posts 47. When in place, the corner-pieces 32, 33 and inset 34 and the planks 30 and 31 are added, and the floor-panel is complete.

20 In the corner of the panel where a column occurs, it is necessary to use either a special corner-piece fitted to the column or else cut away a corner of the cornerpiece and fill it with a special inset 34. To prevent the corner-piece so cut away from spreading, the diagonal gusset 50 is used on the inside, connecting the two side-faces thereof. The inset so introduced may be ornamental, as shown at 44 in Fig. 6, and the edges where it overlaps may be depressed, as shown, but this is unnecessary in ordinary work. The inner or reentrant corner of the corner-piece may have its edges provided with flanges 49 overlapping the flanges 39 of the 25 side-pieces. Beam-bottoms and molds used according to this style of construction for supporting the panel-molds are illustrated in Figs. 3 and 7, the former where the beam has the same depth as the mold, and the latter where it is deeper. The panel-mold is intended to be given the same depth as the minimum beam. The posts 47 support transverse-planks 51, which in turn support edge-planks 52, the latter supporting the 30 several members of the mold individually,

while the beam-bottom 53 is supported at a greater or less height above the planks 51, according to the depth desired, by interposed blocks 54.

Fig. 8 shows a somewhat different form of 70 sheet-metal mold according to my invention, this one being composed of four equal one-piece sides 55 and four equal one-piece corners 56. The corners are made so long as to provide for any variation which may occur in the length and breadth of panels, by causing them to overlap the side-pieces to a greater or less extent. In this case the side-pieces of two opposite sides are secured together by transverse planks 57, which are secured to the gussets 58, in this case shown as of sheet-metal, one on each end and two in the middle of each side-piece; more may be used if found necessary or desirable. Longitudinal planks 59 support the other 75 two sides 55 from the planks 57 in conjunction with two planks 60 extending longitudinally above and below the frame and secured to the planks 57 and 59. The plank 60 may be left in place after hoisting the 80 panel-mold and will not interfere with the placing of my adjustable planks at each side thereof. At one corner 61 is shown an inset 62 adapted to a circular column. The filling-planks are omitted in this illustration. 95 In this sectional mold construction the beam-side as well as the columns may be molded into the ornamental forms used in high class architectural work, so as to give an ornamental cornice in relief around the entire 100 panel, which has not been heretofore practicable in concrete, especially in buildings where cost is an object.

Figs. 10 to 14 inclusive illustrate some 105 possibilities in the way of ornament. In Fig. 10 a fillet 63 is employed between the beam and floor. Fig. 11 shows a cavetto and bead combination; Fig. 12 is a reversed cyma, and Figs. 13 and 14 an upright cyma, in the latter case having ornamental frieze-work impressed in relief. In the last three forms a stiffening angle 64 is employed if necessary for the lower carved portion and also forms an abutment for the lower edge of the frame-plank. 110

Figs. 17 and 18 show a simpler method of 115 corner-formation which are used for general rough work, where nicety of adjustment is not required, or the forms are made to fit the panels in a certain building. In this 120 construction I dispense with the corner-pieces entirely, the side-pieces 65 being directly overlapped at the corners. One of said side-pieces may be provided with a wooden gusset 66 at the corner, and the 125 other side-piece is without a gusset at the corner, as shown.

The panel-mold illustrated in Fig. 19 is similar to that already shown in Fig. 8, except that it is destined to a panel where the 130

1 supporting column is in the center of one side, instead of at the corner, hence in this case one of the four side-pieces 55 is replaced by a special side-piece 67, having a 5 portion of the edge cut out to receive a column inset 68. This panel is destined to receive a sheet-metal plate 69 having the form of an ornamental ceiling rosette stamped in relief thereof, consequently the 10 planks 70, which close the center of the mold, are arranged somewhat differently from those previously shown, the middle ones being somewhat thinner than the outer ones and a part of the planks on the ends 15 of the mold being arranged crosswise as indicated at 71. Of course, these are simply loose planks which need not be cut with beveled edges. When the plate 69 is set in the center, the remainder of the mold 20 surface will be covered by ordinary metal-sheet as usual. The arrangement of the planks in Fig. 19, however, may be used for the adjustable mold to dispense with sheet-metal surfacing, in which case the transversely disposed planks at the ends, or at 25 one end of the mold, would make it unnecessary that the other planks be cut to the length of the panel, provided they are all the same length.

30 In Fig. 21 is shown a mold-form 72 provided with a special stamped ceiling-sheet 23, which is formed in relief, so as to give a paneled or tessellated effect of the resulting concrete. This sheet covers practically the whole surface of the mold, and does not require any additional metal sheets.

Thus far I have spoken more particularly of that construction in which the main and subsidiary beams cross each other at an angle, generally a right angle. However, in many cases the beams run in one direction only, there being no subsidiary beams. In 40 such cases, the panel-molds could still be used, by placing the adjacent sides so as to abut one another, without leaving room for a beam between them. This arrangement is equivalent to narrowing the width of the beam down to nothing, the planks 52 being brought close together and the beam-supports remaining as before. However, it is 45 simpler in such cases to provide an endless mold of the type shown in Fig. 22, in which a number of side-sections 55 are secured together end to end with distance-planks 57, 50 the same as shown in Fig. 8. Some of these side-sections 67 are cut out to permit of column-insets 68, as may be desired, and at the ends special sections 74 are used having 55 quadrantal column-insets 75.

60 In case of the side-sections 35 and 55, it will be found advantageous to introduce in place of intermediate insets longitudinal strengthening devices, whereby the sections can be made much longer than otherwise 65 without any transverse gussets, except upon

the ends. This is especially the case where the sections are made with deep side-faces, the pressure on which of the fluid concrete after pouring exerts a notable bulging effect. For this purpose, I may introduce reinforcing-planks as illustrated in Figs. 23 to 26 inclusive. In Figs. 23 and 24 the strengthening planks 76 are set edgewise to the side-wall 36 of the section, being supported by cleats 77, 78 fastened to the inner faces of 70 the gussets, and projecting metal tabs 79 on their lower edges. In Figs. 25 and 26 the strengthening-plank 80 is secured flatwise against the inner face of the side-wall 36 by means of cleats 81, the lower edge of the 75 plank resting upon the bottom flange 38 of the section. These strengthening-planks, it will be understood, are ordinarily so placed as to be readily removable.

From the above description it will be 85 readily seen that my invention is not limited to special forms and mechanical constructions such as I have hereinabove shown by way of illustration, but that the principles thereof are expressible in a variety of ways 90 as will be well understood by those skilled in the art; therefore the scope of my claims is to be interpreted in view of such alternative constructions.

Having thus described my invention, what 95 I claim as new and desire to secure by Letters Patent is:—

1. An adjustable panel-mold for concrete floor- and roof-work comprising four side-pieces and four corner-pieces mutually adjustable to fit different sizes of floor-panels; 100 means for securing said pieces together in rigid relation; and transverse supports extending across the opening of said frame and below the surface thereof to support a plurality of filling-planks thereon flush with the surface of said pieces.

2. An adjustable panel-mold for concrete floor- and roof-work comprising four side-pieces in opposite parallel pairs, four corner-pieces slidable over the ends of said side-pieces, means for securing said pieces together rigidly in any desired relation; and transverse supports extending across the 110 opening of said frame adapted to support a plurality of filling-planks thereon and with their upper surfaces flush with the frame.

3. A panel-mold for concrete floor- and roof-work comprising a pair of parallel side-pieces, a plurality of transverse beams connecting said side-pieces, a pair of parallel end-pieces, a plurality of longitudinal beams connecting said end-pieces with adjacent transverse beams, corner-pieces forming extensions of said side- and end-pieces and adjustable with relation thereto and completing the outline of the panel.

4. A panel-mold for concrete floor- and roof-work comprising a pair of parallel side-pieces, a plurality of transverse beams con- 130

necting said side-pieces, a pair of parallel end-pieces, a plurality of longitudinal beams connecting said end-pieces with adjacent transverse beams, and corner-pieces fitting over the ends of said side and end-pieces; one or more of said corner-pieces having a portion cut away, and an inset of special form inserted in place thereof.

5. An adjustable panel-mold for concrete floor- and roof-work comprising a plurality of sheet-metal members sliding one over the other and forming sides of adjustable length, each member having a top-face and a side-face; and a downwardly projecting flange 15 formed along the free edge of the top face; and means for securing said members together in rigid relation.
6. An adjustable panel-mold for concrete floor- and roof-work comprising a plurality 20 of sheet-metal members sliding one over the other and forming sides of adjustable length, each member having a top-face and a side-face; an inwardly extending flange formed along the lower or free edge of the side-face: 25 and means for securing said members together in rigid relation.

7. In an adjustable mold for concrete floor- and roof-work, the combination of side-pieces and end-pieces to form a frame 30 having the shape of a panel, said side-pieces being made up of a plurality of sections secured together end to end, and a set of corner-pieces each adjustably sliding over the ends of the adjacent side- and end-pieces.
- 35 8. In an adjustable mold for concrete floor- and roof-work, the combination of side-pieces and end-pieces to form a frame having the shape of a panel, said side-pieces being made up of a plurality of sections secured together end to end; beams connecting opposite side-pieces, and means connecting the adjacent end-pieces to said beams.

- 40 9. In a sectional adjustable panel-mold for concrete floor and roof-work, a side-section 45 comprising a sheet of metal having a top-face and a side-face and one or more transverse gussets on the under side connecting said side-face and top-face together, an inwardly turned flange on the lower edge of said side-face, and a downwardly turned flange on the free edge of said top-face.

- 50 10. In a sectional adjustable panel-mold for concrete floor and roof-work, a sheet-metal section having top-face and side-face, and a pair of transverse gussets connecting said side-face and top-face near each end thereof and separated from the end by a small distance approximately equal to half the thickness of a plank, whereby two of said sections may be secured end to end by bolts connecting two adjacent gussets with a plank between them.

- 55 11. An adjustable panel-mold for concrete floor and roof-work comprising four side- 60 pieces in opposite parallel pairs, each side-

piece comprising a top-face and a side-face and transverse gussets connecting the two faces on the under side, a plurality of transverse beams connecting two opposite side-faces and secured to said gussets, and a plurality of short subsidiary beams extending at right-angles to said first-mentioned beams and each secured at one end to a gusset of the other two side-pieces and at its other end abutting upon and secured to the outermost 75 of said first mentioned beams.

12. An adjustable panel-mold for concrete floor and roof-work comprising four side-pieces in opposite parallel pairs, each side-piece comprising a top-face and a side-face 80 and transverse gussets connecting the two faces on the under side, a plurality of transverse beams connecting two opposite side-faces and secured to said gussets, a plurality of short subsidiary beams extending at right-angles to said first-mentioned beams and each secured at one end to a gusset of the other two side-pieces and at its other end abutting upon and secured to the outermost 85 of said first-mentioned beams, and one or more longitudinal horizontal planks secured to both sets of beams whereby they are held in rigid angular position.

13. An adjustable panel-mold for concrete floor and roof-work comprising four side-pieces in opposite parallel pairs, each side-piece comprising a top-face and a side-face 95 and transverse gussets connecting the two faces on the under side, a plurality of transverse beams connecting two opposite side-faces and secured to said gussets, a plurality of short subsidiary beams extending at right-angles to said first-mentioned beams and each secured at one end to a gusset of the other two side-pieces and at its other end 100 abutting upon and secured to the outermost of said first-mentioned beams, and a plurality of filling-planks resting on said beams and filling the opening between the sides, the top surface of the planks being flush with 105 the top faces of the side-pieces.

14. An adjustable panel-mold for concrete floor and roof-work comprising four side-pieces in opposite parallel pairs, each side-piece comprising a top-face and a side-face 115 and transverse gussets connecting the two faces on the under side, a plurality of transverse beams connecting two opposite side-faces and secured to said gussets, a plurality of short subsidiary beams extending at 120 right-angles to said first-mentioned beams and each secured at one end to a gusset of the other two side-pieces and at its other end abutting upon and secured to the outermost of said first-mentioned beams, a plurality of 125 filling-planks resting on said beams and filling the opening between the sides, and a sheet-metal covering extending over and covering said central opening.

15. In a sectional panel-mold for concrete 130

floor and roof-work, a corner-piece having a top-face and two adjoining side-faces and having open ends and downturned flanges formed on the edges of the reentrant angle of said top-face.

16. In a sectional panel-mold for concrete floor and roof-work, a corner-piece having one angle cut away or suppressed, and a special-formed inset adapted to fit in said 10 cut-away or suppressed angle.

17. A sectional adjustable panel-mold for concrete floor and roof-work comprising, in combination, two opposite lateral sides, each of said sides having a top-face and a side-face and a plurality of transverse gussets uniting said top-face and side-face on the under side, a plurality of transverse beams connecting said opposite lateral sides, each beam being formed of two planks overlapping by a variable amount depending on 20 the size of the panel and having one end of each secured to the gussets of said lateral sides, two end-pieces each having likewise a top-face and side-face and transverse gussets connecting them, means connecting said 25 end-pieces to said beams, and four corner-pieces connecting said lateral sides and end-pieces.

18. An adjustable mold for concrete floor and roof-work comprising, in combination, two opposite lateral sides, each of said sides having a top-face and a side-face and a plurality of transverse gussets uniting said top-face and side-face on the under side, a plurality of transverse beams connecting said 35 opposite lateral sides, a filling of planks supported by said transverse beams substantially flush with said top faces and extending from side to side between the side-members, and a sheet-metal covering over 40 the whole.

19. An adjustable mold for concrete floor and roof-work comprising, in combination, two opposite sides each made up of a plurality of sheet-metal members, each member having a top-face and a side-face and one or more gussets joining them together, distance-members extending between the two sides and connected to said gussets, and a 45 continuous covering from side to side supported by said distance-members; one or 50

more of the members of said sides being cut away at an intermediate point and provided with insets in the position of the columns.

20. A mold for concrete floor and roof-work comprising sheet-metal side-members, each side-member formed in sections separate from each other, distance-members in the nature of beams extending from side to side of said side-members and united thereto, and a set of adjustable planks having beveled edges extending transversely from side to side and between said sections, whereby the area covered by the planks may be varied by reversing one or more planks. 55

21. In a mold for concrete floor and roof-work, a sheet-metal side-member provided with a side- and top-face and a pair of gussets connecting them, a horizontal flange extending inwardly from at or near the bottom of said section, and a projection on the face of each gusset; whereby a plank may be inserted close to the side-wall of said member supported by said flange and confined by said projection. 60

22. In a mold for concrete floor and roof-work, a sheet-metal side-member having a side-face and a top-face and a pair of gussets connecting them, a longitudinal plank 70 removably supported between said gussets and abutting on said side-face, lugs or projections under said plank, and other lugs or projections on said gussets adapted to confine said plank in position against lateral pressure, whereby said plank is caused to 75 support said side-face.

23. A panel-mold for concrete floor and roof-work comprising a pair of parallel side-pieces, a plurality of transverse beams connecting said side-pieces, a pair of parallel 80 end-pieces, a plurality of longitudinal beams connecting said end-pieces with the adjacent transverse beams, and corner-pieces fitting over the ends of said side and end-pieces and 85 slidably adjustable with relation thereto. 90

In witness whereof I have hereunto set my hand in presence of two witnesses.

RUDOLPH B. HARTMAN.
